UNITED STATES PATENT OFFICE.

JAMES R. FINLY, OF DELPHI, ASSIGNOR OF ONE-HALF TO RILEY COBLE,
OF CARROLL COUNTY, INDIANA.

HAME-FASTENER.

SPECIFICATION forming part of Letters Patent No. 276,963, dated May 1, 1883.

Application filed October 21, 1882. (No model.)

To all whom it may concern:

Be it known that I, J. R. FINLY, of Delphi, in the county of Carroll and State of Indiana, have invented certain new and useful Improvements in Hame-Fasteners; and I do hereby declare that the following is a full, clear, and exact description thereof, reference being had to the accompanying drawings, and to the letters of reference marked thereon, which form part of this specification, in which—

Figure 1 is a perspective view of the improved attachment complete. Fig. 2 is a perspective view of the trace-coupling. Fig. 3 is a horizontal cross-section, showing the split hook secured to a hame, which is in section. Fig. 4 is a side view of a trace and the trace-coupling attached thereto.

This invention relates to means for readily and securely attaching traces to the hames; and the nature of my invention consists in a novel self-coupling clip, in combination with a hook which is of peculiar shape, and which is applied to the hame, as will be fully understood from the following description, when taken in connection with the annexed drawings.

The letter A designates a hame, which may be made in the usual well-known manner. In place of and at the usual locality of the common hame-hook or snap-eye, I apply rigidly to the hame a vertically-split coupling-ring, B. This ring B is formed on or suitably secured to a plate, C, which is oblong and concave laterally and transversely, and the coupling-ring is constructed with a vertical slot, a, which separates its two ends and forms a passage for a coupling-clip, F, which will interlock with said ring, and which will under all ordinary circumstances prevent casual detachment of the parts.

E designates a trace, which has secured to its end a clip, F, adapted to engage with the vertically-split coupling-ring B. This trace-clip F is of peculiar construction, and it is especially adapted for coupling with the vertically-split ring B on the hame A. The trace-clip is composed of a shank, which is riveted between the two strips forming the trace E.

The part protruding beyond the end of the trace has a transversely-slotted neck, the top portion of which terminates in a circular head

or cap, a'. The bottom portion has shoulders at c c and a contracted portion or tongue, d, terminating in a short cylindrical pivot, b, which is united to the cap a'. The width of the contracted portion d is slightly less than the space a between the ends of the split coupling-ring B. Thus by adjusting this portion d so that it will register with the said space, and dropping it down, the pintle b can be brought within the coupling-ring B, thus effecting a coupling between the trace and the hame. The split or space a between the ends of the coupling-ring is in front. Consequently when the trace is drawn back in its normal position it will be impossible for the parts to casually uncouple. To effect an uncoupling the clip F must be turned forward until the contracted part d will register with the space a between the ends of the ring B, and then this clip must be raised perpendicularly.

It is obvious from what I have above stated that I have a clip-coupling without a spring which will not under any circumstances become disengaged. It is perfectly safe, and at the same time it can be readily uncoupled or coupled by hand.

It will be seen that I construct the vertically-split hame-ring or socket-piece B with an oblong plate, C, which is especially adapted, by reason of its vertical and lateral curvature, to be applied to a hame, A, thus allowing the said hame-ring or socket-piece to be rigidly secured to a hame.

Having thus fully described my invention, what I claim as new, and desire to secure by Letters Patent, is—

The combined hame and trace fastener, consisting of the vertically-split hame-ring and concave plate C, in combination with a trace-clip formed of a transversely-slotted portion having a pivotal extremity and a contracted portion, d, adapted to pass the slit between the ends of said split ring, substantially in the manner and for the purposes described.

In testimony that I claim the foregoing as my own I affix my signature in presence of two witnesses.

JAMES R. FINLY.
